COMBINATION CAP AND SCREW DRIVER FOR CONTAINER OF LIGHTER FLUID

Charles A. Byrne, Washington, D. C.

Application January 4, 1956, Serial No. 39,596

Term of patent 14 years

(Cl. D58—26)

FIG. 1

FIG. 2

FIG. 3

FIG. 4

Fig. 1 is a front elevation of a combination cap and screw driver for container of lighter fluid embodying my new design;

Fig. 2 is a side view of the combination cap and screw driver shown in Fig. 1, looking at the left side;

Fig. 3 is a bottom view of the combination cap and screw driver shown in Fig. 1, looking upward; and

Fig. 4 is a front elevation of the combination cap and screw driver shown in Fig. 1.

The broken lines shown in Fig. 4 of the drawing are for illustrative purposes only.

I claim:

The ornamental design for a combination cap and screw driver for container of lighter fluid, as shown and described.
